UNITED STATES PATENT OFFICE.

HAROLD J. SMITH, OF CHICAGO, ILLINOIS, ASSIGNOR OF ONE-HALF TO HENRY F. BAKER, OF CHICAGO, ILLINOIS.

MUSIC-ROLL-PERFORATING MACHINE.

1,401,201.

Specification of Letters Patent. Patented Dec. 27, 1921.

Application filed February 19, 1920. Serial No. 360,020.

To all whom it may concern:

Be it known that I, HAROLD J. SMITH, a citizen of the United States, and a resident of the city of Chicago, in the county of Cook and State of Illinois, have invented certain new and useful Improvements in a Music-Roll-Perforating Machine; and I do hereby declare that the following is a full, clear, and exact description of the same, reference being had to the accompanying drawings and to the numerals of reference marked thereon, which form a part of this specification.

This invention relates to an improved type of a machine adapted to automatically and simultaneously perforate a plurality of music roll ribbons by means of electrically controlled solenoids which govern the operation of the punching knives.

It is an object of this invention to provide a machine adapted to automatically perforate a plurality of music roll ribbons at the same time to duplicate a master music roll also adapted to be perforated by said machine.

It is also an object of the invention to provide a machine wherein solenoids are used for governing the operation of the perforating members.

Another object of the invention is the construction of a music roll perforating machine wherein an eccentric mechanism is provided for operating a punch bar the perforating knives of which are automatically controlled by solenoids the operation of which is governed by the perforations in a master roll.

A further object of the invention is to provide a music roll perforating machine wherein a perforated master roll is adapted to co-act with a plurality of spring contact makers which are adapted to establish contacts through the master roll perforations and thereby energize solenoids for the purpose of causing the same to automatically control the operation of perforating knives operable by a punch bar for simultaneously perforating a plurality of music roll sheets to correspond with the perforations in said master roll.

It is an important object of this invention to provide a music roll perforating machine of comparatively simple and effective construction to permit a plurality of music

roll sheets or strips to be perforated at the same time to duplicate the perforations of a master roll which governs the operation of electrically controlled perforating mechanisms.

Other and further important objects of this invention will be apparent from the disclosures in the drawings and specification.

The invention (in a preferred form) is illustrated in the drawings and hereinafter more fully described.

On the drawings:

Figure 1 is a side elevation of a perforating machine embodying the principles of this invention.

Fig. 2 is a transverse section thereof taken on line 2—2, of Fig. 1, showing parts in elevation.

Fig. 3 is a longitudinal section taken on line 3—3, of Fig. 2.

Fig. 4 is an enlarged fragmentary detail section of the die and punch mechanisms, showing the punch bar in its lowermost position.

Fig. 5 is a section taken on line 5—5, of Fig. 4, showing the punch bar in its upper position.

Fig. 6 is a fragmentary plan view taken on line 6—6 of Fig. 1.

Fig. 7 is an enlarged detail section taken on line 7—7 of Fig. 6.

Fig. 8 is a sectional view taken on line 8—8 of Fig. 7.

Fig. 9 is an enlarged fragmentary detail section taken on line 9—9 of Fig. 1, showing parts in elevation.

Fig. 10 is an enlarged detail section taken on line 10—10 of Fig. 1, showing the master rolls in elevation.

Fig. 11 is a fragmentary elevation of the master roll gears.

Fig. 12 is an enlarged vertical section taken through one of the solenoids.

Fig. 13 is a wiring diagram of a solenoid circuit.

As shown on the drawings: The reference numeral 1 indicates a metal base provided with an opening 2 in the top thereof. Rigidly mounted on the top of the base 1 are two oppositely disposed supporting frames or walls 3 and 4, each having an integral upwardly extending arm 5, shaped to afford shoulders 6. A vertical slot 7 is provided in each of the frame arms 4, for

slidably receiving the grooved end portions of a transverse punch bar 8. Axially formed on the ends of the punch bar 8, are trunnions 9, for receiving the upper ends of connecting or driving rods 10. Journaled in the side frames 3 and 4, are the ends of a transverse horizontal shaft 11, on the middle portion of which is secured a pulley wheel or fly-wheel 12, adapted to be driven by a belt 10 or other suitable means. Keyed or otherwise secured on the projecting ends of the shaft 11, are eccentrics 13, which engage in openings in the lower ends of the rods 10. Washers 14 and nuts 15 are used for retaining 15 the rods 10 in position on the trunnions 9 and the eccentrics 13.

Pivottally connected to one of the rods 10, is one end of a link 16, the other end of which is pivottally connected to the middle 20 portion of a lever or arm 17. The lever 17, has its upper end rotatably engaged on a stub shaft 18, secured to project outwardly from the side of the frame 3. Rotatable on said stub shaft is a bevel gear 19, to the 25 outer side of which is rigidly secured a ratchet wheel 20, also rotatable on said stub shaft 18. A check pawl 21 is pivottally mounted on the outer side of the frame 3, to fall by spring pressure into engagement with 30 the teeth of the ratchet wheel 20, to prevent a reverse rotation thereof. Secured on the lower end of the lever 17, is a driving pawl 22, the end of which is engaged with the toothed periphery of the ratchet wheel to 35 actuate the same when the lever 17 is operated. Secured on the outer surface of the frame 3, are bearings 23, for rotatably supporting a horizontal shaft 24. Keyed or otherwise secured on one end of the shaft 40 24, is a bevel pinion 25, which is in mesh with the bevel gear 19, to receive a drive therefrom. Secured on the other end of the shaft 24, is a worm 26, which meshes with a worm-wheel 27, secured on the outer 45 end of one of the trunnions 28, which are provided at the ends of a master or driving roll 29. The trunnions 28, are journaled in suitable openings provided in the frames 3 and 4. Mounted on the other roll trunnion 50 28, to the outside of the frame 4, is a gear 30, which is adapted to mesh with a similar gear 31, secured on one of the trunnions 32, of an upper feed roll 33. The upper feed roll trunnions 32, project through vertical 55 key-hole slots 34, provided in the frames 3 and 4, as shown in Fig. 10, to permit vertical adjustment of said upper roll 33. Vertical drillings are provided in the frames 3 and 4, for receiving blocks 35, which are adjustably held against the trunnions 32, by 60 springs 36, and adjusting cap screws or bolts 37, provided with lock nuts 38.

Journalled in the frames 3 and 4, adjacent the upper feed roll 33, is a guide roll 39. 65 Also journaled in the frames 3 and 4, to the

inside of the guide roll 39, and in the same horizontal plane therewith is a switch or contact roll comprising a cylindrical metal core 40, and an outer cylindrical upper contact sleeve 41, which is insulated from the 70 core 40, by a sleeve of insulating material 42. As clearly shown in Fig. 3, guide rolls 43, 44, 45, 46 and 47, have the trunnions thereof journaled in the frames 3 and 4. The guide rolls 43, 46 and 47, are disposed in 75 the same horizontal plane with the rolls 33, 39 and 41, while the rolls 44 and 45 are positioned in a plane above the rolls 43 and 46. A perforated master music roll ribbon or strip 48 is trained to run over the upper 80 feed roll 33, around the bottom of the guide roll 39, and up over the contact sleeve 41, then around the roll 43, and back again below the sleeve 41 and the guide roll 39, to run between the feed rolls 29 and 33. At 85 the feeding or entrance end of the machine a plurality of superimposed blank music roll ribbons or strips 49, are fed over the roll 47, and between the guide rolls 47 and 46, then up over the rolls 45 and 44, from 90 which point said ribbons are run between the rolls 44 and 43, and out of the machine between the driving rolls 29 and 33, completely perforated as hereinafter more fully described. 95

Projecting through the frame 3, is a binding post 50, which is insulated from said frame by an insulation sleeve or collar 51. Engaged on the inner end of said binding post 50, is a spring contact finger or brush 100 52, the free end of which is positioned to frictionally ride on the contact sleeve 41, as shown in Fig. 7. Connected to the binding post 50, is one end of a conductor wire 53, the other end of which is connected to a 105 source of electrical energy, such as batteries 54.

Rigidly secured on the upper edges of the frames 3 and 4, above the switch cylinder 41, is a cross strip or bar 54, to which is hingedly connected a mounting board 55, by means of hinges 56. The mounting board is hingedly mounted to permit access to be had to the under side thereof. Mounted in spaced relation on the mounting board 55, are a 110 plurality of offset or staggered rows of binding posts 57, one post for each of the respective rows of note perforations of the master music roll. The capacity of the master music roll 48, in this instance is arranged for ninety-nine rows of perforations, so that there are ninety-nine binding posts 57 on the board 55. Each binding post 57 has connected to the lower projecting end thereof one end of a resilient or spring contact member or brush 58, the curved free end of which is adapted to ride over the master music roll ribbon 48, to track in its corresponding longitudinal row of note perforations. The solid portions of the master 115 120 125 130

music roll ribbon act to insulate or break the contact between the contact sleeve 41, and the respective contact brushes 58.

Supported on the frame shoulders 6, and 5 by means of posts or legs 59, are two apparatus boards or tables 60, positioned on opposite sides of the frame arms 5. Mounted on the under side of the tables 60, are a plurality of staggered or offset rows of solenoids 61, one for each of the corresponding binding posts 57. The capacity of one of the tables 60, is for forty-nine solenoids, while the other table has fifty solenoids mounted thereon. Each solenoid 61 is provided 10 with a soft metal core 62, to the upper end of which is pivotally connected the lower end of a link 63. The upper end of each link 63, is pivotally connected to one end of a bell crank 64, which is supported 15 on the table by a slotted block 65. Pivoted to the other arm of each bell crank 64, is one end of a connecting rod or pin bar 66, to the end of which is pivotally secured a pin 67. The pins 67, slidably project into 20 horizontal pin-ways or drillings 68, provided in opposite sides of the punch bar 8, as shown in Fig. 5. Also provided in the punch bar 8, are a plurality of vertical knife-ways or punch-ways 69, which cross the respective 25 horizontal pin-ways 68. Referring to the wiring diagram of Fig. 13, it will be seen that one terminal of each solenoid is connected to its respective binding post 57, by a conductor wire 70, while the other solenoid terminal is 30 connected by means of a conductor wire 71, to the batteries 54.

The perforating mechanisms are disclosed in detail in Figs. 4 and 5. Secured in the bottom portions of the vertical frame 35 slots 7, by means of bolts 72, are the ends of a platen 73, provided with a row of vertical drillings or openings 74. Secured on the upper surface of the platen 73, is a die plate 75, having a row of die openings 76, therein 40 which register with the platen openings 74. An apertured stripper plate 77 is separated from the die plate 75, by spacer blocks 78. A space 79, is thus afforded between the die plate 75 and the stripper plate 77, to permit 45 the music roll ribbons 49, to pass between said die plate 75, and the stripper plate 77. Spacer blocks 80, are supported on the end portions of the stripper plate 77, to space an apertured top or upper knife guide plate 50 81 above the stripper plate. The retaining bolts 72 are threaded into the frames 3 and 4, for securely holding the platen 73, the die plate 75, the stripper plate 77, and the upper knife guide plate 81, secured in position. Hung below the punch bar 8, by 55 means of bolts 82 is an apertured lower knife guide plate 83, which is spaced from the punch bar by means of spacer sleeves or collars 84, engaged around the bolts 82 between the punch bar and said lower guide 60

plate 83. A plurality of punches or knives 85, are provided for doing the perforating. In this case, ninety-nine knives are provided in a row. Each knife 85, is provided with a collar 86, at about the middle portion thereof and between the stationary guide plate 81 and the movable guide plate 83. As shown in Fig. 4, the knives 85 slidably project through the stationary guide plate 81, upwardly into the punch bar openings 65. The lower or cutting ends of the knives 85, slidably project through the movable guide plate 83, and the stripper plate 77, for coaction with the openings 76, in the die plate 75, and the openings 74, in the 70 platen 73.

The operation is as follows:

With the improved music roll perforating machine constructed as shown and described, a plurality of blank music roll 85 sheets or ribbons 49, disposed one above the other, may be simultaneously cut or perforated to duplicate the perforations in a master music roll sheet or ribbon 48, which is conducted around suitable rolls and discharged from the machine together with the plurality of perforated superimposed ribbons which entered the machine in blank form. 90

As shown in Fig. 3, the perforated master 95 music roll ribbon 48, enters the machine over the upper feed roll 33, passes beneath the idler or guide roll 39, and up over the switch or contact cylinder or sleeve 41, which is connected to one side of the batteries 54^a, by means of the brush 52, and the wire 53. From the switch cylinder 41, the master ribbon 48 is trained around the roll 43, and passes out of the same end of the machine between the feeding rolls 29 and 33. 100

A drive is imparted to the primary driving or feed roll 29, from the main pulley or fly-wheel 12, which is adapted to be rotated by means of a belt from any suitable source of power. Rotation of the pulley 12, causes 110 rotation of the shaft 11 and the eccentrics 13, which being rotatable in openings in the lower ends of the arms or rods 10, act to reciprocate the same to alternately raise and lower the punch bar 8. The eccentric movement of the rods 10, acts to swing the lever 17, back and forth by means of the link 16. The swinging movement of said lever 17, causes the driving pawl 22 to engage the teeth of the ratchet wheel 20 and thereby 115 rotate the ratchet wheel and the bevel gear 19 secured thereto. The bevel pinion 25, in mesh with the bevel gear 19, is thus rotated, thereby causing rotation of the shaft 24 and the worm 26. The worm 26 rotates the 120 worm wheel 27, and a drive is thus imparted to the main or lower driving or feed roll 29. The gear 30, connected with the roll 29, drives the gear 31, and thereby causes rotation of the upper roll 33. The music roll 125 130

ribbons are thus fed through the machine over and between the respective rolls as hereinbefore described. The feed rolls 29 and 33, and the punch bar 8, are thus operated 5 simultaneously from the same source, namely the pulley wheel 12.

Referring to Figs. 3 and 7, it will be seen that all of the switch brushes or fingers 58, ride over the surface of the perforated master ribbon 48, in position to track in the respective lines of apertures and slots covering the eighty-eight notes of a player piano. As the master ribbon passes over the switch cylinder 41, and below the brushes 58, the 10 brushes project through the master openings in the ribbon 48, and contact the switch cylinder 41. Circuits are thus closed with the respective solenoids 61, as will be apparent from the circuit diagram shown in Fig. 13. The 15 respective solenoids 61, are thus energized and act to draw the respective solenoid cores 62, upwardly thereby moving or tipping the respective bell crank 64, into the dotted line position of Fig. 12. The respective pin bars 66, are thus moved inwardly toward the punch bar 8, thereby causing the respective pins 67 to enter the pin-ways 68, crossing the punch-ways 69, to serve as stops against which the upper end of the punches 20 or knives 85 abut to prevent upward sliding of said knives in the punch bar ways 69. Downward movement of the punch bar 8, causes the inwardly projecting pins 67, to force the respective knives 85, downwardly 25 whereby the lower or cutting ends of said respective knives 85, cut through or punch the plurality of superimposed blank ribbons 49, which pass through the opening 47, between the stripper plate 77, and the die plate 30 75, as shown in Fig. 4. With the return or upward movement of the punch bar 8, the movable guide plate 83, engages the collars 86, of the depressed knives and acts to retract or elevate the knives from their cutting 35 or punching positions. The plate 77, acts to strip the perforated ribbons 49, from the knives 85, when the punch bar 8, returns to its upper position.

The operation of the solenoids are controlled by the switch brushes 58, which coact with the openings in the master music roll ribbon 48, to cause the proper knives 85, to be depressed by the punch bar 8, to cut or punch apertures or openings in the ribbons 49, to duplicate the perforations in the master music roll ribbon. Either a single cut or a plurality of successive cuts may be made by a knife to provide single circular openings or elongated slots in the ribbons 49. A plurality of music roll ribbons may thus be simultaneously cut or punched to duplicate the perforations in the master music roll ribbon 48. From the roll 43, the ribbon 48, and the perforated ribbons 49 pass 60 65 out of the machine together between the

rolls 29 and 33. The operations of the solenoids govern the operations of the cutter knives 85, by means of the pins 67, since the make and break contacts of the brushes 58, with the contact cylinder 41, completely control the opening and closing of the electrical circuits to the solenoids. 70

It will, of course, be understood that the number of binding posts 57 and the number of solenoids may vary to correspond to the 75 number of notes to be recorded on the music roll ribbons, the capacity of which vary with the size of the player piano key-boards.

As described, ninety-nine binding posts 57, are provided on the contact board 55. 80 Eighty-eight of the binding posts are used for the eighty-eight notes in a player piano, while the remaining binding posts are used for expression levers and other purposes.

I am aware that many changes may be 85 made, and numerous details of construction may be varied through a wide range without departing from the principles of this invention, and I therefore do not purpose limiting the patent granted hereon otherwise than 90 necessitated by the prior art.

I claim as my invention:—

1. In a perforating machine the combination with a die mechanism, of a punch mechanism adjustably mounted to co-act therewith, said punch mechanism having vertical and horizontal openings therein, each of said horizontal openings meeting and extending beyond one of said vertical openings and each of said vertical openings meeting and extending beyond one of said horizontal openings, whereby said openings are in pairs and the openings of each pair cross each other, cutter knives adjustably carried by said punch mechanism and slideable in said vertical openings, a plurality of pins, mechanisms connected with said pins for actuating the same, and means controlling the operation of said mechanisms to cause said pins to slide into said horizontal openings to co-act with said cutter knives to cause the same to cut. 100 105 110

2. In a cutter head for sheet perforating machines, a set of rod-shaped reciprocatable cutters, a projection on each cutter and a stationary guide on the opposite side of said projections from the cutting ends of the cutters coöperating with said projections to limit the motion of the cutters away from their work, said guide completely surrounding each of said cutters and means for reciprocating the cutters. 115 120

3. In a cutter head for sheet perforating machine, a platen, a die plate thereon, a stripper plate spaced from the die plate a distance equal to the thickness of the set of sheets to be perforated, a guide plate on the side of said stripper plate opposite the platen, said platen, die plate, stripper plate and guide plate each having holes, the holes 125 130 135

- being in sets, each set including one hole in each plate, and the holes of each set being aligned with each other, cutters reciprocating in and guided by said holes, one cutter for each set of holes, a projection on each cutter between said guide plate and stripper plate, and a means located between said projections and the stripper plate for moving said cutters away from said die plate.
- 10 4. In a cutter head for sheet perforating machines, a punch bar, means for moving said bar toward and away from the sheets to be punched, said bar having a series of holes each parallel to the direction of said motion, a series of rod-shaped cutters, one in each of said holes, the cutters fitting in and being guided by said holes, said bar having a second series of holes each at an angle to the direction of motion and each crossing one hole of the first mentioned series of holes and extending from one surface of the bar beyond the hole it crosses, a series of reciprocatable members mounted in and guided by said second series of holes, one in each hole, and means for selectively reciprocating said members between a position in which they are wholly free from the first named holes and a position in which they extend across the first named holes, whereby, when in the last named position, each of the members is supported by the bar on both sides of the hole it crosses.
- 25 5. In a sheet perforating machine, means for drawing through the machine a set of sheets to be perforated and for drawing through the machine a master sheet, said means including a pair of rolls contacting respectively the master sheet and one side of the set of sheets to be perforated and pressing said master sheet against the other side of said set of sheets to be perforated, and means for driving said pair of rolls simultaneously whereby the master sheet and the set of sheets to be perforated are constrained to move through the machine at the same rate of travel.
- 30 6. In a cutter head for sheet perforating machines, a set of rod-shaped reciprocatable cutters, a projection on each cutter and a stationary guide on the opposite side of said projections from the cutting ends of the cutters coöperating with said projections to limit the motion of the cutters away from their work, said guide completely surrounding each of said cutters, means for reciprocating said cutters, said means including a guide moving with the cutters and contacting with them between said projection and their cutting ends.
- 35 In testimony whereof I have hereunto subscribed my name in the presence of two subscribing witnesses.
- 40 HAROLD J. SMITH.
